UNITED STATES PATENT OFFICE.

EDWARD L. MOONEY, OF MINNEAPOLIS, MINNESOTA, ASSIGNOR TO COSBY-WIRTH
MANIFOLD BOOK COMPANY, OF MINNEAPOLIS, MINNESOTA, A CORPORATION OF
MINNESOTA.

SALES-BOOK COVER.

Application filed November 30, 1927. Serial No. 236,662.

My present invention relates to a sales book cover and has for its object the provision of a simple and highly efficient sales book and tissue book holders therefor, and to this end the invention consists of the novel devices and combinations of devices herein-after described and defined in the claims.

In the accompanying drawings, which illustrate the invention, like characters indicate like parts throughout the several views.

Referring to the drawings:

Fig. 1 is a perspective view of a sales book cover and a sales book and a tissue book held therein by means of the improved holders;

Fig. 2 is a fragmentary perspective view of the sales book cover opened to show the tissue book holder;

Fig. 3 is a fragmentary detail view in section taken on the line 3—3 of Fig. 1, on an enlarged scale;

Fig. 4 is a fragmentary detail view in section taken on the line 4—4 of Fig. 2, on an enlarged scale;

Fig. 5 is a fragmentary plan view of the parts shown in Fig. 1, on an enlarged scale;

Fig. 6 is a fragmentary perspective view of the sales book as shown in Fig. 1 with the sales book and tissue book removed;

Fig. 7 is a fragmentary detail view in section taken on the line 7—7 of Fig. 5, on an enlarged scale; and

Fig. 8 is a fragmentary detail view in section taken on the line 8—8 of Fig. 6, on an enlarged scale.

The sales book cover illustrated comprises a back section 9, an intermediate section 10, and a cover section 11. Said intermediate section 10 is hinged to the right-hand longitudinal edge of the back section 9 for folding movement thereon and the cover section 11 is hinged to the left-hand longitudinal edge of the back section 9 for folding movement onto said intermediate section.

A holder for a sales book A is permanently and rigidly attached to the upper face of the intermediate section 10 at the top thereof and comprises a flat metal base plate 12, an abutment 13 and a bail 14. Said base plate 12 extends substantially the full width of the intermediate section 10 and its upper edge portion is turned perpendicular to the upper face of said intermediate section, and then folded inward upon itself to form an abutment 13. The abutment 13 has a tubular bead 15 in the angle between said abutment and the

base plate 12. The outer end portions of the arms of the bail 14 are bent laterally toward each other to form a pair of trunnions 16 pivotally mounted in the tubular bead 15 and to attach said bail to the abutment 13 for swinging movement toward and from the intermediate section 10.

The arrangement of the leaves and carbon sheets comprising the sales book A is well known and for the purpose of this case it is thought sufficient to simply state that the leaves on which the triplicate copy is made and the carbon sheets are attached by staples B to a back C and the sheets on which the original copy is made are formed with the free ends of the attached leaves and folded thereon.

In attaching the sales book A to the intermediate section 10 by means of the improved holder, the back C of said book is inserted between the arms of the bail 14 until stopped by the staples B, as best shown in Fig. 7. In this position of the sales book A its top engages the abutment 13 and is held by the bail in contact therewith so that the sales book A is firmly held against endwise or angular movements on the intermediate section 10 and the arms of the bail hold said book against lateral shifting movement on said intermediate section.

Permanently attached to the lower end of the section 10 at the left-hand corner thereof is a thumb piece 17 by which said section may be opened and closed.

Used in conjunction with the sales book A is a tissue book D on the leaves of which a duplicate copy is made. This tissue book D is attached to the back section 9 at the left-hand edge thereof by an improved holder in a manner in which the leaves of said book may be folded one at a time between the uppermost leaf of the book A and its underlying carbon sheet. The holder for the tissue book D is rigidly and permanently secured to the upper face of the back section 9 and comprises a flat metal base plate 18, a clamping flange 19 and a co-operating clamping bail 20. The clamping flange 19 is formed by bending the outer longitudinal edge portion of the base plate 18 perpendicular to the back section 9 and then folding the same inward upon itself. The inner longitudinal edge portion of the base plate 18 is folded upon itself to form a tubular bead 21 and the end portions of the arms of the bail 20 are

bent laterally toward each other and pivotally mounted in the ends of the tubular bead 21.

To attach the tissue book D to the back section 9 by means of the improved holder, the back section of the cover of said book is inserted between the arms and the bail 20 when positioned as shown in Fig. 4, and said bail pressed downward to clamp said back section between the flange 19 and said bail, as shown in Fig. 3. It will be noted that the height of the flange 19 is such as to hold the tissue book D so that one leaf thereof can be inserted between the uppermost leaf of the sales book A and the underlying carbon sheet and with the used leaves of said tissue book interposed between the intermediate section 10 and back section 9. The unused portion of the tissue book D rests on the inner face of the top section 11.

The position in which the tissue book D is held by the flange 19 and bail 20, as shown in Fig. 3, is highly important in that it permits the leaves thereof to project completely transversely across the sales book A, as shown in Fig. 1, in order that all indicia written on the uppermost leaf of said sales book will appear in duplicate on the underlying leaf of said tissue book. After the uppermost leaf of the book A has been filled in, the salesman lifts the intermediate section 11 by means of a thumb piece 17 and thereby withdraws the leaf of the tissue book D from the sales book A and allows the same to drop onto the back section 9. The intermediate section 10 is then returned to its normal position in which it rests on the used leaves of the tissue book D. The salesman then detaches the leaves containing the original and triplicate copy from the book A by tearing the triplicate sheet from the book A at its bound upper end. The uppermost leaf of the tissue book D on the cover section 11 is then placed between

the uppermost leaf of the book A and the underlying carbon, ready for the necessary entries at the time the next sale is made. The bail 20 and co-operating clamping flange 19 securely hold the tissue book D on the back section 9 and may be readily detached from the sales book cover simply by lifting the bail 20 and withdrawing its back section of its cover therefrom.

What I claim is:

1. A sales book cover comprising a back section, an intermediate section, a cover section and a tissue book holder on the back section comprising a fixed base plate having an upstanding clamping flange and a bail pivoted to the base plate at a distant point from the clamping flange and normally extending toward the clamping flange with its transverse portion co-operating therewith to clamp one of the covers of the tissue book between the clamping flange and bail and secure the tissue book to the sales book cover.

2. A sales book cover comprising a back section, an intermediate section, a cover section and a tissue book holder on the back section comprising a fixed base plate having an upstanding clamping flange, and a clamping bail pivoted to the base plate at a distant point from the clamping flange with its transverse portion co-operating therewith to clamp one of the covers of the tissue book between the clamping flange and bail and secure the tissue book to the sales book cover with said cover of the tissue book intermediately folded at substantially right angles with one section thereof extending substantially parallel to the clamping flange and with the other section thereof extending between the arms of the clamping bail and between said back and intermediate sections.

In testimony whereof I affix my signature.

EDWARD L. MOONEY.
